UNITED STATES PATENT OFFICE.

LEON ARTHUR HALLSTEAD, OF BUFFALO, NEW YORK.

AIR-PRESSURE GAUGE.

Application filed May 27, 1925. Serial No. 33,230.

My invention relates to improvements in air pressure gauges, and the object of the invention is to construct an air line nozzle in which is incorporated a manually actuated valve for controlling the passage of air through the nozzle, the movement of such valve actuating a second valve for controlling the passage of air into the air pressure gauge which is incorporated in the nozzle.

10 A further object of the invention is to provide resilient means in the air pressure gauge for assisting in the movement of the gauge when low air pressures are being registered as is the case in registering the air pressure in balloon tires.

My invention consists of an air pressure gauge constructed and arranged all as hereinafter more particularly described and illustrated in the accompanying drawing in

20 which:—

Fig. 1 is a plan view of my device.

Fig. 2 is a vertical sectional view through the line 2—2 Figure 1, the manually actuated valve being shown in the depressed or 20 open position to permit the passage of air through the nozzle, the air pressure gauge being in the inoperative position.

Fig. 3 is a similar view to Figure 2. The manually actuated valve being shut and the 30 means for permitting air to enter the air pressure gauge being open, such gauge being shown in the operative position.

Fig. 4 is an enlarged part sectional detail of the air pressure recording means.

35 Like characters of reference indicate the corresponding parts in the different views.

1 designates a substantially tubular casing provided in its outer end with the nozzle chamber 2, the outer end of which is threaded and adapted to receive the shouldered bushing 3, which is threaded thereinto.

4 is the rotatable outer end of the nozzle which is turned over at right angles to the main portion and provided on its outer end 45 with an orifice 5 adapted to receive the plunger 6 which is designed to open the automobile tire valve in the usual manner when the nozzle is applied thereto, the plunger 6 being resiliently held in position by means of spiral spring 7. The rotatable portion 4 is provided on its inner end with a reduced portion 8 adapted to be inserted into the orifice 9 of the bushing 3 and held in engagement therewith by the lock nuts 10 and 11 which are threaded onto the end of the portion 8.

12 is a washer constructed of rubber or

similar material and adapted to be inserted between the nut 10 and the inner face of the bushing 3, and 13 is a passage in the outer end of the nozzle leading from the orifice 5 to the outer end of the portion 8.

The casing 1 is provided with a substantially cylindrical chamber 14 and an air passage 15 both of which communicate with the nozzle chamber 2, the chamber 14 being adapted to receive the pressure gauge which we shall now describe. The outer end of the chamber 14 which communicates with the nozzle chamber 2 is threaded and receives a threaded bushing 16 which has a reduced portion 17 on its inner face, and 18 is a passage extending through the bushing 16 and the reduced portion 17. 19 is a sleeve of the same diameter as the chamber 14 and adapted to slide therein, such sleeve being 70 interiorly threaded and receives the plug 20 which has a reduced inner portion 21 of the same diameter as the portion 17. The inner end of the portion 17 is slightly reduced and receives the outer end of a rubber sleeve or 75 pocket 22, the other end of which is sealed and in contact with the face of the portion 21.

23 is a spiral spring which constitutes a flexible metallic covering for the rubber sleeve 22, its ends encircling the respective portions 17 and 21. 24 is a spiral spring of slightly less diameter than the sleeve 19 and adapted to encircle the wire covering 23 of the rubber sleeve 22 being inserted between the inner face of the bushing 16 and the sleeve 19, one end of the spring being attached to such sleeve. 25 is a slot in one end of the chamber 14, through which the end of the sleeve 19 can be seen, and 26 is a 80 graduated scale in proximity to the slot 25 being provided on the outer face of the nozzle.

27 is a transverse bore formed in the casing 1 at the closed end of chamber 14 and 100 adapted to receive the inlet valve actuating plunger which is reciprocal therein. The main portion of the plunger consists of two cone shaped members 28 and 29 connected at their reduced ends by the stem 30, and 31 is a centrally disposed stem extending upwardly from the upper face of the cone shaped member 28 and provided with a button 132 which is of approximately the same diameter as the passage 27 and adapted to 110 slide therein when it is depressed. 32 is a flange formed integrally with the portion

1 and provided in the passage 27 to act as a stop for the plunger therein, and 33 are a pair of fibre or rubber washers of the same diameter as the passage 27 and inserted 5 thereinto one on either side of the flange 32. 34 is a plug which is inserted into the lower end of the passage 27, and 35 is a spiral spring interposed between such plug and the lower face of the cone shaped member 29, 10 such spring being adapted to restore the plunger to its uppermost or closed valve position when the button 132 is released as is shown in Figure 3.

The inner end of casing 1 is formed to 15 provide an air inlet valve chamber 36, the outer end of which is internally threaded and receives the threaded bushing 37 upon which the end of the air line hose is secured. 38 is a circular passage extending 20 from the inner end of the inlet valve chamber 36 to the vertical passage 27, such orifice being opposite the stem 30 when the plunger 39 is in the uppermost or inoperative position. 39 is a circular valve having its inner face recessed to receive the rubber washer 40 which engages a circular lip 41 upon the inner end of the chamber 36, and 42 is a valve stem which is centrally secured to the valve 39 and slidable in the passageway 25 when the valve is opened. 43 is a spiral spring interposed between the outer face of the valve 39 and the bushing 37, such spring being provided to keep the face of the rubber washer 40 in close contact with the lip 41 when the valve is closed.

For preventing the air entering the air pressure gauge whilst the tire is being inflated, I incorporate the following described device in my nozzle. In the passageway 15, 40 a rod 44 is provided, one end of such rod being designed to project from the passage 15 into the transverse bore 27 and be in contact with the lower cone shaped member 29 of the plunger, the other end of the rod being 45 designed to project into the nozzle chamber 2 being turned upwardly and carrying a circular plunger 45 upon its upper end. 46 is a reduced portion preferably constructed of rubber or like material, and centrally disposed upon the inner face of the plunger 45, and 47 is a spiral spring interposed between the outer face of the plunger 45 and the inner face of the lock nut 11. 48 is a circular recess centrally positioned in the outer face 50 of the bushing 16, being of the same diameter and adapted to receive the portion 46 when the plunger 45 moves inwardly to close the end of the orifice 18 and prevent air entering the air pressure gauge.

60 The operation of my device is as follows:

When the nozzle is applied to the automobile tire valve in the usual manner, the manually actuated plunger is in the position illustrated in Figure 3, the valve 39 being closed and the plunger 45 being re-

moved from the bushing 16 as the rod 44 is pushed outwardly by the cone shaped member 29 which is in its uppermost position. As the tire valve is opened by means of the plunger 6, the air from the tire enters the 70 nozzle passing inwardly through the passage 13 into the nozzle chamber 2 and from thence through the passage 18 into the rubber sleeve 22 expanding such sleeve longitudinally and moving the sleeve 19 along the 75 cylindrical chamber 14 and as the exterior of the slot 25 is suitably graduated the air pressure of the tire will be shown.

If it is seen that the tire requires further inflating the button 132 is depressed, 80 its movement causing the conical portions 28 and 29 to move downwardly into the position shown in Figure 2. It will be seen that as the conical portion 28 moves downwardly, the valve stem 42 will be pushed 85 outwardly into the direction of the orifice 40 and the valve opened which will permit the air pressure from the air line to pass around the valve and valve stem through the passageways 38, 27, and 15, and from 90 thence through the passage 13 into the tire valve in the usual manner. While the valve 39 is being opened, the plunger 45 will close the orifice 18 in the bushing 16 as the rod 15 will be permitted to move inwardly under 95 the influence of the spiral spring 47 as the conical member 29 moves downwardly. It will thus be seen that while the tire is being inflated, no air is permitted to enter the air pressure gauge.

When it is considered that the tire is sufficiently inflated and the air pressure in the tire required to be taken, the button 132 is released and the cone shaped members 28 and 29 will move upwardly under the influence of the spiral spring 47. 105 As they make this movement, the valve 39 will close, thus cutting off the passage of air from the air line and the rod 44 and the plunger 45 will move outwardly through the upward movement of the cone shaped member 29, thus the air from the tire will be again admitted to the valve as before described and the air pressure of the tire recorded.

Since the introduction of balloon tires it 110 has been found difficult to insure that one gauge will accurately show both low and high pressures, so to overcome this difficulty we have inserted the spiral spring 24 between the sleeve 19 and the bushing 16 as 115 before described. When the gauge is in the inoperative position, this spring is under compression, and when air is admitted under low pressure to the gauge, it assists pushing the sleeve 19 along the passageway 120 14. When a predetermined sufficiently high pressure has been reached, the sleeve 19 to which the end of the spring 24 is attached 125 will travel to a point where the other end of the spring will not be in contact with the 130

bushing 16 as illustrated in Figure 3 and therefor will not further assist the gauge movement.

From the foregoing description, it will be seen that I have devised a very simply constructed air line nozzle and tire pressure gauge which will be of great value to motorists in the saving of both time and trouble. Furthermore, I have devised means for preventing the entry of air to the pressure gauge during the process of inflating the tire and have thus eliminated a continual strain on the gauge.

My device also insures that the motorist records the correct air pressure in his tire, and not the air pressure in the air line, which is very often the case where no means is provided for cutting off the air line pressure from the air pressure gauge, during the process of inflation.

What I claim for my invention is:—

1. A combined air line nozzle and pressure gauge comprising a substantially tubular casing presenting an inlet valve chamber at one end, a nozzle chamber at the opposite end, a longitudinal cylindrical chamber closed at its inner end and opening at its outer end into the nozzle chamber, an air passage paralleling the cylindrical chamber and connecting the nozzle chamber with the air inlet chamber, a valve controlling communication between the air inlet chamber and the air passage, a sliding gauge operable in the cylindrical chamber in response to air pressure in the nozzle chamber, a manually controlled valve operating in the nozzle chamber and controlling communication thereof with the aforesaid cylindrical chamber and a nozzle secured in and closing the nozzle chamber but removable therefrom to give access to both the

gauge and the valve operating in the nozzle chamber.

2. A combined air line nozzle and pressure gauge comprising a substantially tubular casing presenting an inlet valve chamber at one end, a nozzle chamber at the opposite end, a longitudinal cylindrical chamber closed at its inner end and communicating at its outer end with the nozzle chamber, a transverse bore formed in the casing between the closed end of the cylinder and the inlet valve chamber, an air passage paralleling the cylindrical chamber and connecting the nozzle chamber with the transverse bore, a normally closed valve located in the inlet chamber and controlling communication thereof with the transverse bore, a stem carried by the valve and protruding into said bore, a sliding gauge operable in the cylindrical chamber in response to air pressure in the nozzle chamber, a normally closed valve controlling communication between the nozzle chamber and the open end of the cylindrical chamber, a stem carried by the last named valve and extending through the air passage into said transverse bore, a manually operable plunger reciprocal in said bore and formed with spaced conical portions adapted for sliding engagement with said valve stems to move the valves to open position, the arrangement of said conical portions with reference to the valve stems being such that when one valve is open the other valve is closed whereby either the air passage or the gauge may be placed in communication with the interior of a tire, and a nozzle secured in the nozzle chamber and removable therefrom to give access to the gauge and to the valve operating in said nozzle chamber.

LEON ARTHUR HALLSTEAD.
